UNITED STATES PATENT OFFICE.

JOHN JOSEPH DALY, OF NEWTON CENTER, MASSACHUSETTS.

SHOE.

Application filed August 17, 1923. Serial No. 657,938.

To all whom it may concern:

Be it known that I, JOHN J. DALY, a citizen of the United States, residing at Newton Center, county of Middlesex, Commonwealth of Massachusetts, have invented certain new and useful Improvements in Shoes, of which the following is a specification.

This invention relates to double soled shoes, and involves certain improvements over and refinements upon the shoe described and illustrated in my prior Patent No. 1,468,284, granted September 18, 1923, to which reference is made as showing the particular type of shoe involved herein.

15 In such a shoe the outer and intermediate soles are attached to the upper by independent lines of stitching whereby the outer sole when worn through may be readily disconnected from the intermediate sole by cutting the line of stitches which attaches said sole to the intermediate sole and severing said outer sole across the breast of the heel. This exposes the intermediate sole as a new unworn and complete wear surface attached 20 to the upper by a line of stitching which theretofore was covered and protected by the outer sole.

In order to avoid the liability of cutting into the intermediate sole when the outer sole is being removed and also to reduce to the minimum the length of the severing cut at the heel breast in removing said outer sole, I propose to weaken the outer sole transversely by forming therein a narrow 30 slot located as close to the heel breast as possible and terminating just short of the lines of stitching which attach the outer and intermediate soles to the upper. In removing the outer sole, therefore, all that is required 35 is to cut through said sole at the edges thereof instead of cutting clear across the sole as was previously necessary. This reduces to the minimum the liability of cutting so deeply as to penetrate the intermediate sole, 40 but in order to avoid all possibility of injuring the intermediate sole I may interpose a metallic blade deflecting member between the outer and intermediate soles and underlying said slot. This member may be 45 either a metallic shank piece interposed be-

tween the outer and intermediate soles or a simple pronged reinforcement plate driven into the intermediate sole at the heel breast and underlying said slot. In fact where such a reinforcement is used the slot itself 55 may be dispensed with if desired, although the slot is desirable in that it reduces the necessity for making a severing cut entirely across the outer sole.

For the purposes of this application, I 60 shall show and discuss my invention in its adaptation to a welt shoe. It will be understood, however, that such treatment is purely illustrative and in no way limiting. The construction of my shoe is described and 65 illustrated in the accompanying specification and drawings, and the characteristic features of novelty are particularly pointed out in the appended claims. Throughout the specification and drawings like reference 70 characters are correspondingly employed, and in the drawings:

Fig. 1 is a side elevation of a shoe in accordance with my invention.

Fig. 2 is a fragmentary top plan view at 75 the toe thereof.

Fig. 3 is a fragmentary bottom view at the heel breast particularly showing the weakening slot and the underlying knife blade deflecting plate, the outer sole being 80 in place.

Fig. 4 is a view similar to Fig. 3 but with the outer sole removed.

Fig. 5 is a section on the line 5—5 of Fig. 3 and diagrammatically illustrating the formation of the weakening slot across the 85 outer sole.

Fig. 6 is a fragmentary side elevation of the shoe and also indicating the formation 90 of such slot.

Fig. 7 is a detail view of the knife blade deflecting plate shown in Figs. 3, 4 and 5, and

Fig. 8 is a bottom view of a modification in which the deflecting plate shown in 95 Fig. 7 is omitted and in its place a metallic shank substituted between the outer and intermediate soles.

I have indicated at 1 the upper and at 2 the welt of a double soled welt shoe in ac- 100

- cordance with my invention. Stitched or otherwise fastened to the welt 2 at 3 is an intermediate sole 4 preferably of resilient but wear resisting cushioning material.
- 5 This sole conforms in outline to and is substantially co-extensive with the outer sole 5 which is stitched at 6 to the intermediate sole and welt by a line of fastenings independent of and outside of the fastenings 3
- 10 which secures the intermediate sole to the welt. The soles 4 and 5 are thus independently stitched onto the welt, the stitching 3 being normally covered and protected by the outer sole 5 when said sole is in place.
- 15 Preferably the intermediate sole 4 is a full sole and the outer sole 5 is a three quarter sole terminating beyond the breast 7 of the heel 8.
- When the outer sole is worn through, it 20 may be readily disconnected from the intermediate sole by severing the stitches 6 and cutting across said sole at the heel breast whereby to expose the intermediate sole as a new, complete, and unworn wear surface, 25 said intermediate sole itself being securely attached to the welt by its own independent line of stitching 3.
- In order to reduce the length of the severing cut which must be made across the 30 outer sole at the heel breast, I preferably slot said sole as close to the heel breast as possible. This slot is indicated at 9, Figs. 3, 5 and 6, and terminates short of the edges of the outer sole and just within 35 the line of stitches 6 so that in severing the outer sole it is simply necessary to cut the unsloated portions thereof at the stitching. This not only simplifies the operation of removing the outer sole when 40 worn through, but reduces the danger of cutting so deeply into the outer sole as to injure the intermediate sole.
- In order to avoid all possibility of cutting into the intermediate sole, however, I 45 may interpose a blade deflecting element between the outer and intermediate soles and underlying the slot 9. In Fig. 7 this element is shown as a simple plate 10 having prongs 11 by means of which it may 50 be driven into the intermediate sole. In Fig. 8 I show a pronged metallic shank piece 12 interposed between the outer and intermediate soles and extended sufficiently forward to underlie the slot 9. In addition to its blade deflecting function, the 55 plate 10, or shank piece 12, also serves to stiffen and reinforce the shoe in the region of the shank.
- The slot 9 may be formed in the outer 60 sole in a variety of ways, as by means of the ordinary breasting knife or by means of the special concavo convex cutter 13 shown in Figs. 5 and 6 which is mounted on an arbor 14 journaled in a guide 15. 65 By means of this construction the guide 15
- may be brought against the extremities of the curved breast of the heel and the cutter moved across the heel breast between said extremities to form the slot 9 in the outer sole between the lines of stitching 6. 70 Various other modifications in the form and construction of my invention may obviously be resorted to if within the limits of the appended claims.
- What I therefore claim and desire to secure by Letters Patent is:
1. In a shoe, an outer sole and an intermediate sole secured to the upper by independent attaching means, said outer sole being weakened between its edges adjacent the breast of the heel to permit it to be readily severed from the intermediate sole. 80
2. In a shoe, an outer sole and an intermediate sole secured to the upper by independent attaching means, said outer sole 85 being weakened between its edges adjacent the breast of the heel to permit it to be readily severed from the intermediate sole, and a blade deflecting element interposed between the outer and intermediate soles 90 and underlying said weakened portion of the outer sole.
3. In a shoe, an outer sole and an intermediate sole secured to the upper by independent attaching means, said outer sole 95 being weakened between its edges adjacent the breast of the heel to permit it to be readily severed from the intermediate sole, and a blade deflecting element interposed between the outer and intermediate soles 100 and underlying said weakened portion of the outer sole, and comprising a metallic plate having attaching prongs adapted to be driven into one of said soles. 105
4. In a shoe, an outer sole and an intermediate sole secured to the upper by independent lines of stitching, said outer sole having a slot thereacross adjacent the breast of the heel and terminating inside of the lines of stitching to permit said sole 110 to be readily severed from the intermediate sole.
5. In a shoe, an outer sole and an intermediate sole secured to the upper by independent lines of stitching, said outer sole 115 having a slot thereacross adjacent the breast of the heel and terminating inside of the lines of stitching to permit said sole to be readily severed from the intermediate sole, and a blade deflecting element interposed 120 between the outer and intermediate soles and underlying said slot.
6. In a shoe, an outer sole and an intermediate sole secured to the upper by independent lines of stitching, said outer sole 125 having a slot thereacross adjacent the breast of the heel and terminating inside of the lines of stitching to permit said sole to be readily severed from the intermediate sole, and a blade deflecting element interposed 130

between the outer and intermediate soles be readily severed from the intermediate sole.

metallic plate having attaching prongs adapted to be driven into one of said soles.

- 5 7. In a shoe, an outer sole and an intermediate sole secured to the upper by independent attaching means, said outer sole having a portion thereof adjacent the breast of the heel removed to permit said sole to

In testimony whereof I affix my signature in presence of two witnesses.

JOHN JOSEPH DALY.
